UNITED STATES PATENT OFFICE.

LAURENCE OWEN McGOURTY, OF NEW YORK, N. Y.

RAZOR-BLADE HOLDER.

Application filed April 3, 1926, Serial No. 99,560.

This invention relates to razor blade holders, an object of the invention being to provide a simple, inexpensive device into which a razor blade of the safety razor type may be readily inserted, securely held and properly positioned for use either as a knife or, more especially, for use as a holder to sharpen or hone the blade.

A further object is to provide a device of this character which requires no means for holding the blade other than the clamping action of the holder itself and requires no manual adjustment of the holder to receive and accommodate the blade.

With these and other objects in view, the invention consists in certain novel features of construction and combinations and arrangements of parts, which will be more fully hereinafter described and pointed out in the claims.

In the accompanying drawings—

Figure 1 is a view in side elevation of my improved blade holder;

Figure 2 is an end view of Figure 1;

Figure 3 is a view in transverse section on the line 3—3 of Figure 1;

Figure 4 is a view in transverse section on the line 4—4 of Figure 1;

Figures 5 and 6 are views of opposite edges which constitute the upper and lower edges of the holder shown in Figure 1, the blade being omitted.

My improved razor blade holder comprises a pair of strips 1 and 2, which are preferably of wood or other non-metallic material having the necessary strength, flexibility and elasticity for the purpose intended.

These strips are of any desired length and are located side by side or superimposed one on the other and rigidly secured together adjacent one end. As securing means I have illustrated rivets 3 which are projected through both strips 1 and 2, and this end of the device in which the rivets are projected constitutes the handle of the razor blade holder, the other end of the device constituting the blade receiving end.

Over the back or rear edges of the strips 1 and 2 at its blade receiving end, I secure a channel-shaped metal clamp 4, this clamp being secured to the strips by inwardly indenting the clamp at both sides thereof, forming lugs 5 which project into the strips 1 and 2. This metal clamp 4 may be of brass or any other suitable material which will

rigidly hold the strips 1 and 2 together at the back and rear edges thereof.

It will be noted that the clamp extends over or partially across the outer face or transverse dimension of each strip, so that the pressure of the opposite side portions of the same act to cause the forward or leading edge portions of the strips 1 and 2 at the blade-receiving end have a tendency to flare apart, as shown in Figure 2. Also, the longitudinal edges of the opposite sides of the clamp 4 are disposed in the approximate plane of the longitudinal centers of the strips so as to effect a positive clamping of the parts together, and whereby the pressure aforesaid will be uniformly exerted on the inserted edge portion of the blade throughout its length.

6 represents a safety razor blade which is readily positioned between the strips 1 and 2, and this can be best accomplished by first forcing one end of the razor blade 6 between the strips 1 and 2, then swinging the blade to a position parallel to the edges of the strips 1 and 2. The inner edge portion of the blade will be securely clamped or sustained between the strips 1 and 2 by the pressure exerted on the engaged rear edge portions of the latter by the opposite side portions of the clamp 4, while the intermediate portion of the blade will be substantially free from contact with the flared forward or leading edge portions of the strips 1 and 2, so that the natural flexibility of the blade will be practically unrestrained for proper and efficient stropping or honing purposes. It is to be noted that the edge of the blade between the strips will not be injured as there will be a uniform and even pressure on the opposite sides of the blade and the blade will come into contact with no metal parts which might otherwise injure the same.

When the blade is thus positioned in the device it can be manipulated for any purpose, the primary use, as above stated, being to hold the blade for sharpening or honing.

While I have illustrated a particular type of blade, it is obvious that the invention is not limited to the particular blade employed, and various slight changes and alterations might be made in the general form of the parts described without departing from my invention, and hence I do not limit myself to the precise details set forth but consider

myself at liberty to make such slight changes and alterations as fairly fall within the spirit and scope of the appended claims.

I claim:

- 5 1. A blade holder comprising a body formed of a pair of elongated strips, one superimposed on the other, said strips being secured together to one side of the transverse center of the same and forming a handle portion, and a resilient clamp engaged over the edges of both of said strips at the rear side of the body and at the other side of the transverse center thereof, the longitudinal edges of said clamp being disposed 10 in an approximate plane of the longitudinal center of said body whereby the pressure of the opposite sides of the clamp acts to flare the forward edge portions of said strips to permit greater flexing of the blade positioned 15 between the strips and the rear edge portion only of the blade is clampingly sustained by the pressure of the forward edge portions of the opposite sides of the clamp.

2. A blade holder comprising a body formed of a pair of strips, one superimposed on the other, means for permanently securing said strips together at one side of the transverse centers thereof to form a handle portion, and a clamp engaged over the edges of both of said strips at the rear side of the body and at the other side of the transverse center thereof, the longitudinal edges of said clamp being disposed inwardly of the engaged rear edges of the strips and parallel thereto, whereby the pressure of the opposite sides of the clamp acts to flare the forward edge portions of said strips to permit greater flexing of a blade positioned between the strips and the rear edge portion only of the blade is clampingly sustained by the pressure of the forward edge portions of the opposite sides of the clamp, the flexing of the clamped blade acting to increase the frictional clamping effect on the same of the clamped portions of said strips.

LAURENCE OWEN McGOURTY.
